GENERATOR

René A. Baudry and Ernest I. Pollard, Pittsburgh,
Pa., assignors to Westinghouse Electric Cor-
poration, East Pittsburgh, Pa., a corporation
of Pennsylvania

Application May 27, 1944, Serial No. 537,588

2 Claims. (Cl. 171—252)

Our invention relates to the cooling of enclosed dynamo-electric machines and more particularly the stator-laminations thereof, although the invention is also applicable to the cooling of rotor-laminations. Our invention more particularly relates to the cooling of a machine in which the useful magnetic flux passes substantially radially through the core-laminations which are to be cooled, which is a characteristic feature of the stator-member of some inductor-type electrical generators.

Our invention is an improvement over the inductor-generator structure which is shown in our Patent 2,315,653, granted April 6, 1943, for a hydrogen-cooled motor-generator set. In the previously used construction, as shown in said patent, the hydrogen was cooled by means of a cooler which was placed in the central section of the motor-generator unit, around the coupling between the generator-shaft and the motor-shaft, and about half of the heat produced in the generator-windings was carried off in this manner, the other half of the heat being removed by means of a water-cooler built in the stator-core of the generator. The cost of this separate, centrally located cooler in the motor-generator set, was quite high, and the labor-cost of the extensive pipe-fitting which was involved was another considerable item of expense.

The object of our present invention is to provide a much simpler generator-construction, with a much simpler water-cooling system and piping-system, having greater accessibility, and resulting in a machine of much lower cost.

A more specific object of our present invention is to provide a construction in which all of the heat which is produced in the generator-windings may be withdrawn by means of the cooler which is built in the stator-core. We accomplish this by utilizing the stator-core which is somewhat larger, thus demanding a somewhat larger stator-frame, but the stator-frame and the core-laminations are relatively cheap, compared with the cost and inconvenience of the double-cooler ventilating-arrangement which is shown in our aforesaid patent. In the enlarged stator-core laminations of our generator, we provide ventilating ducts which are disposed between the coolant-circulating ducts of the water-cooler and the outer periphery of the core, and we provide baffling and ventilating means for causing the hydrogen or other gaseous ventilating medium to recirculate, flowing axially in the air-gap in one direction, and back through the aforesaid ventilating ducts in the other direction. The water-pipes are

5 passed longitudinally through the core, in good heat-exchanging relation to both the stator-windings and the ventilating ducts, the water-tubes occupying an intermediate position between these two parts which are to be cooled.

With the foregoing and other objects in view, our invention consists in the combinations, structures, elements, systems and methods hereinafter described and claimed, and illustrated in the accompanying drawing, wherein Figure 1 is a longitudinal sectional view of the top half of a hydrogen-cooled high-frequency inductor-type generator, and Fig. 2 is a fragmentary view illustrating the construction of one of the stator-core punchings.

10 The inductor-type electrical generator which is illustrated in the drawing comprises a stator member 3 and a rotor member 4, separated by an air-gap 5. The stator member 3 is illustrated as comprising a plurality of cylindrical magnetizable yokes 6A, 6B, and 6C which are disposed in alignment with each other, in such manner that the axial flow of magnetic flux from one yoke-portion directly across to the next adjacent one is at 15 least partially restricted, by any means which limits the amount of this magnetic flux-flow, as by means of non-magnetizable rings 7 and 8, which are welded between the corresponding ends of the successive sections of the magnetizable yokes 6A, 6B and 6C.

20 Suitable field-coil means are employed for energizing the generator, and there are various ways of mounting said means. In the preferred form of embodiment of our invention, as illustrated, the excitation-means consists of two field-coils 9 and 10 which surround the respective non-magnetizable rings 7 and 8, and which are, in turn, surrounded by annular magnetizable members 12 and 13, which complete a flux-path around the 25 coils 9 and 10, respectively.

30 In the illustrated embodiment of our invention, we utilize four laminated magnetizable stator-core members 14A, 14B, 15B, and 15C, which are carried by the bores of the cylindrical yoke-members 6A, 6B, and 6C. The core-sections 14A and 14B are on opposite sides of the non-magnetizable ring 7, while the core-sections 15B and 15C are on opposite sides of the non-magnetizable ring 8.

35 The laminations of which the various stator-core members are composed are of special construction, in accordance with our invention, as shown at 14 in Fig. 2. These several stator core laminations 14 have axially aligning winding-receiving slots 16 in their bores, said slots receiving the stator-winding 17, which is connect-

ed to terminal-leads 18. Back of the winding-receiving slots 16, in good heat-transfer relation thereto, and preferably (but not necessarily) spaced slightly therefrom, the respective laminations 14 are provided with axially aligned coolant-receiving holes 20, which receive pipes 21 through which cooling-water is circulated, through externally connected means, as indicated by the arrow 22. Back of the coolant-receiving holes 20, the several laminations are provided with axially aligned ventilating ducts 23, which are disposed in good heat-transfer relation to the coolant-receiving holes 20, being preferably spaced slightly therefrom, and being disposed between said coolant-receiving holes 20 and the outer periphery of the laminations.

The rotor-member 4 comprises a pair of magnetizable annular members 24A and 24B. The rotor-member 24A cooperates with the north and south stator-cores 14A and 14B, respectively, which are magnetized by the coil 9; and the rotor-member 24B cooperates with the south and north stator-cores 15B and 15C, respectively, which are magnetized by the coil 10. These annular rotor-members 24A and 24B are provided with inductor-type peripheral tooth-projections 25 which cooperate with the stator-slots 16 to produce tooth-flux pulsations so as to induce high-frequency current in the stator winding-conductors 17. The north and south-pole teeth of either the stator-member or the rotor-member have to be offset 180 electrical degrees, or the thickness of one tooth, with respect to each other, in order that the induced electromotive forces may add to each other in the winding 17. In order that the coil-sides of the winding 17, which lie in the stator-slots 16, may be straight, it is preferred to have the stator-slots 16 aligned axially with each other, as described, while the rotor-teeth 25 which are under stator-cores of opposite polarity are staggered with respect to each other.

The machine is totally enclosed in a gas-tight housing which includes the stator cylinder-member 6A—7—6B—8—5C, closed at its two ends by end-brackets 26 and 27, or by any other gas-tight closure-means. The interior of the space within the generator-housing is filled with hydrogen, or other gaseous ventilating medium. We provide an internal gas-recirculating system by means of suitable baffles and blowers. At one end, the stator is provided with an annular baffle 30 which directs the recirculating gaseous medium into a rotor-carried fan 31 at that end of the rotor. At the other end of the machine, the electrical connections 32 may constitute a baffle which directs the gaseous cooling medium into a rotor-borne fan 33 at that end of the rotor. The recirculating path for the gaseous ventilating medium is from each of the fans 31 and 33 into the air-gap 5, flowing axially or longitudinally inwardly along the air-gap, from each end of the machine, to a central portion, where an annular space 34 makes it possible for the combined streams of gas to flow radially outwardly and enter the ventilating ducts 23, through which the gas now flows longitudinally or axially in the opposite direction, emerging from the two extreme ends of the ventilating ducts 23, and circulating around back again into the fans 31 and 33, respectively.

In operation, the internal heat, generated within the machine, is withdrawn by the water which is circulating in the pipes 21. Heat is radiated to these pipes 21 from both sides, by

reason of the nearness of said pipes to both the winding-receiving slots 16 of the stator-core laminations, and the ventilating ducts 23 of the same laminations. In this way, some of the heat 5 which is generated is withdrawn by direct conduction to the cooling-pipes 21, while the rest of the heat is withdrawn through the medium of the recirculated gaseous medium which, in turn, is cooled by heat-radiation to the outer 10 peripheries of the cooling-pipes 21.

It will be noted that the inductor-type generator, which is ventilated by our new means, is a machine which is generally characterized by a core-member which does not have much depth 15 in the radial direction, because the flux travels radially in the stator-core, the north and south poles being displaced from each other in a longitudinal or axial direction. In dynamo-electric machines in which the north and south poles 20 are displaced circumferentially with respect to each other, it is customary and necessary to provide stator-cores which are deeper in the radial direction, so as to provide for the circumferentially flowing flux which flows back of the stator 25 windings. Our new inductor-type generator is distinctive in having stator-cores which are abnormally deep (for a radial-flux core) in the radial direction, so as to make room for the ventilating-ducts 23. It is noted, however, that these 30 ventilating-ducts 23 are preferably longer in a radial direction than in a circumferential direction, as shown in Fig. 2, so as to facilitate the radial flow of the magnetic flux.

From the foregoing description and explanation, 35 it will be apparent that we have provided an extremely simple and economical construction for ventilating a hydrogen-cooled machine, or other totally enclosed machine, particularly a machine of the high-frequency inductor-type, as set forth in the original statement of objects of our invention.

We claim as our invention:

1. An inductor-type electrical generator comprising a stator-member and a rotor-member; 45 said stator-member comprising a plurality of cylindrical magnetizable yokes disposed in alignment with each other in such manner that the axial flow of magnetic flux from one cylindrical magnetizable yoke directly across to the adjacent one is at least partially restricted, field-coil means encircling the ends of the cylindrical magnetizable yokes in such manner as to overlie the place where the axial flow of magnetic flux from one cylindrical magnetizable yoke directly across to the adjacent one is at least partially restricted, annular magnetizable means surrounding said field-coil means for completing a magnetic path around the same, a laminated magnetizable stator-core member disposed within each cylindrical magnetizable yoke, the stator-core laminations having winding-receiving slots in their bores, coolant-receiving holes close to said winding-receiving slots, and ventilating ducts close to 55 the coolant-receiving holes, between said coolant-receiving holes and the outer peripheries of said laminations, externally connected means for circulating a coolant axially through said coolant-receiving holes, and stator-windings disposed in 60 said stator-core slots; said rotor-member being a magnetizable annular inductor-type rotor-member disposed within the bore of said stator-core members with an air-gap in between, and having peripheral tooth-projections, and baffling and ventilating means arranged in such manner as to 65

cause a gaseous ventilating medium to recirculate, flowing axially in one direction through at least a portion of the length of the air-gap, and flowing axially in the other direction through at least a portion of the length of said ventilating ducts.

2. The invention as defined in claim 1, characterized by said baffling and ventilating means being arranged to provide two recirculating paths for the gaseous ventilating medium, flowing 10

axially inwardly through each half of the air-gap from each end of the rotor-member to the approximate center of the length of the rotor-member, then flowing radially outwardly to said ventilating ducts, then returning to the two ends of the machine through said ventilating ducts.
